UNITED STATES PATENT OFFICE.

AUGUSTUS ALLGOEVER, OF NEW YORK, N. Y., ASSIGNOR OF ONE-HALF TO
GEORGE JESHURUN, OF SAME PLACE.

WOVEN-WIRE MATTRESS.

SPECIFICATION forming part of Letters Patent No. 451,704, dated May 5, 1891.

Application filed March 11, 1890. Serial No. 343,449. (No model.)

To all whom it may concern:

Be it known that I, AUGUSTUS ALLGOEVER, of the city, county, and State of New York, have invented a new and useful Improvement 5 in Woven-Wire Mattresses or Bed-Bottoms; and I do hereby declare that the following is a full and exact description thereof, reference being had to the accompanying drawings, and to the letters of reference marked thereon, 10 making a part of this specification.

My invention relates to woven-wire mattresses or bed-bottoms, and has for its object to re-enforce the same and prevent such an excessive sagging thereof as will have a tendency 15 to strain the coils and produce their permanent elongation.

It consists in combining with the woven-wire mattress an underlying, undergirding, supporting web or netting of interwoven 20 wires, which are free to yield in the direction of the length of the coils of the mattress to an extent sufficient to allow a proper elastic play in said coils and no more, and will thereupon afford an unyielding support for the 25 mattress under every part thereof, so as to resist its undue depression or straining either in the direction of the length of its coils or transversely thereto.

In the accompanying drawings, Figure 1 is 30 a bottom view of my improved re-enforced woven-wire bed-bottom; Fig. 2, a longitudinal section thereof in line *z z* of Fig. 1; Fig. 3, a similar detached section illustrating a modification in structure of the re-enforcing netting; Fig. 4, a similar section illustrating the 35 function of the re-enforcing netting in supporting the mattress when it is depressed; Fig. 5, a detached view of a portion of the netting to be combined with the mattress, 40 illustrating a modification thereof.

A A represent the bars of a frame to which the ends of the woven-wire mattress B are secured in any approved manner. The elastic woven-wire web of the mattress is constructed, 45 as is usual, of interwoven strands of spirally-coiled spring-steel wire, the coils being made preferably to extend the length of the mattress. In use of the elastic coils thus combined to afford an elastic bed the strain of 50 the pressure of a weight placed thereon is resisted wholly by the longitudinal elasticity of

the interlocking coils; but the several coils are left wholly without lateral support, so as to be free to give and play loosely *inter se* in a direction transversely to their length. To 55 limit the depression and extension or sagging of these several longitudinal coils under the strain of a weight thereon and to afford them at the same time transverse support, I place under said woven-wire mattress a metallic 60 re-enforcing web or netting D, formed of a series of interwoven or interlocked wires secured to the frame upon which the mattress B is secured, so that the wires in said re-enforcing web shall severally extend in a direction 65 transversely to that of the spiral coils in the superimposed mattress and the web have a firm support upon each end of the mattress.

By preference the interwoven wires of the netting D are severally bent in zigzag fashion, 70 each to form a succession of flattened coils or loops *c c*, comparatively non-elastic in their length, as shown in Figs. 1 and 2. They may, however, be formed in spiral coils, as shown in Figs. 3 and 4, to form elastic strands which 75 shall be stretched to extend transversely to the length of the coils of the mattress. In either case they are left loose and free to move independently in the direction of the length 80 of the coils of the mattress B, their play or freedom of movement being, however, so limited as that they will only give or yield far enough to allow a depression of the superimposed mattress to the extent required in a proper elastic play thereof, whereupon they 85 will so engage each other as to afford an unyielding support to the mattress, as shown in Fig. 4. This limit to the play or freedom of movement in the meshes of the supporting-netting D in the direction of the length of the 90 superimposed mattress B is obtained by overlapping the several wire strands of the netting at their interlocking bends, as is illustrated in an exaggerated form at *e e* in Figs. 1, 2, and 3, whereby an independent motion thereof 95 is permitted until the open spaces between them are closed by the contact of the interlocked strands, as shown in Fig. 4, and by securing the outermost wires at each end of the netting to the end bars A A of the frame, so 100 as to give the netting rigid support when the limit of its play is reached.

As a modification of my invention, the supporting or re-enforcing web or netting D, to be combined with the woven-wire mattress B as an undergirding therefor, may be constructed of a metallic net or mail D', composed of a series of separate interlocking links ff, as shown in Fig. 5.

I claim as my invention—

1. The combination, in a mattress, with a suitable supporting-frame, of the independent woven-wire fabrics stretched upon said frame one above the other, with the length of the coils in the one disposed at right angles to the coils in the other, substantially in the manner and for the purpose herein set forth.

2. The combination, with a woven-wire mattress and a frame-work for its support, of a system of loosely interwoven or interlocking longitudinally-bent wires stretched under the mattress transversely to the length of its coils and secured to said frame-work, substantially in the manner and for the purpose herein set forth.

In testimony whereof I have signed my name to this specification in the presence of two subscribing witnesses.

AUGUSTUS ALLGOEVER.
